CLAMP

Charles W. Card, Aurora, Ill.

Application October 29, 1936, Serial No. 108,205

7 Claims. (Cl. 24—81)

This invention relates to improvements in clamps, particularly adapted, though not necessarily limited in its use for securing electric light cables to the branches of a tree, and one of the objects of the invention is to provide an improved clamp of this character for separately gripping both the branch and the light cord or cable.

Heretofore considerable difficulty and inconvenience has been experienced in placing illuminating lamps upon trees, especially out of door trees, when the temperature is very low, as considerable time is generally required, and by reason of the operator's hands becoming cold, it has been difficult to handle and anchor the lamps and light cords.

It is therefore another object of the present invention to provide an improved clamp of this character that may be readily and quickly applied to both the branch of the tree and the light cord or cable and as readily removed, and which when in position will be held against accidental displacement.

A further object is to provide an improved clamp of this character that will be simple, durable and cheap to manufacture, and efficient and effective in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a perspective view of a clamp of this character constructed in accordance with the principles of this invention, showing the same applied in use.

Figure 2 is a longitudinal sectional view taken on line 2—2, Figure 1.

Figure 3 is a detail transverse sectional view taken on line 3—3, Figure 2.

Figure 4 is a detail sectional view taken on line 4—4, Figure 2.

Figure 5 is a view similar to Figure 2 showing the clamp in a partially open position.

Figure 6 is a view similar to Figure 5 showing the clamp in a full open position.

Figure 7 is a top plan view of Figure 2.

Figure 8 is a bottom plan view of the tongue member.

Referring more particularly to the drawing, the clamp consists essentially of a body portion 10, constructed of any suitable material having more

or less inherent resiliency, and may be of any desired size and configuration.

One end of the body 10, is bent back upon itself to form a hook shaped extremity 11, extending over and being spaced from the body. The free extremity of the hook shaped portion terminates considerably short of the opposite end of the body. An aperture 12, is provided in the hook shaped portion 11, preferably adjacent the free extremity of such portion, and if desired, reinforcing ribs 13, may be formed or provided in the hook shaped extremity and the adjacent portion of the body 10. The numeral 14 designates generally a tongue member, the extremity 15, of which is of a length slightly greater than the space between the body portion 10 of the clamp and the opposed portion of the hook shaped end 11.

The hook member is pivotally connected to the extremity of the portion 11, in any desired or suitable manner, preferably by forming a hook or loop 16, which passes through the aperture 12, and is curved or bent about the extremity of the portion 11, thereby forming a hinge or pivot, with respect to the body portion of the clamp, and about which pivot the tongue is adapted to swing when the free extremity of the element 14 is moved toward or away from the body portion.

The portion 16, may be formed in any suitable manner, preferably by cutting out a portion of the material from which the hook is formed and then bending the cut out portion into proper shape.

At the lateral edges or extremities of the portion 15 of the tongue, deflected portions 17 are provided to reinforce or strengthen the tongue.

At any suitable point between the extremity of the portion 14 of the tongue and the inclined portion 15, there may be provided a recess 18, formed by bending or shaping the tongue. This recess is closed by the body portion 10, when the tongue is moved into an operative position.

By reason of the inherent resiliency in the body portion 10, and the length of the portion 15 of the tongue, it will be manifest that when the parts are in the position shown in Figure 5, and it is desired to move the parts into the position shown in Figures 1 and 2, the body portion 10 will yield or spring under the stress of the portion 15 of the tongue, sufficiently to permit the tongue to be moved into a closing position. The resiliency of the body 10, after the portion 15 of the tongue has passed from the position shown in Figures 3 and 5, to the position shown in Figure 2, will cause the body 10 to assume a normal position,

and the tongue will be temporarily locked in its adjusted position.

In use the tongue is moved to the full open position shown in Figure 6. The clamp may then 5 be placed upon a branch 19 of a tree, the inclined portion 15 of the tongue, in this position of the parts of the clamp, will co-operate with the body 10, to serve as a guiding means for directing the clamp into position upon the branch of the tree.

10 The clamp may then be partially closed, that is, the tongue is moved to the position shown in Figure 5, after which the light conductor wire or cord may be placed in position against the face of the inclined portion of the tongue or against the 15 edge of the deflected portions, of flanges 17. The tongue may then be moved into the position as shown in Figure 2, at which time the body 19 will form a closure for the recess 18, and, as the tongue when in the position shown in Figure 2 20 will be temporarily locked, it will be manifest that both the branch of the tree and the electric light cord or wire will be held in position, one with relation to the other.

It will therefore be manifest that with this 25 improved construction there is provided a clamp which will be simple and will be very effective and efficient in operation. Furthermore the clamp is adapted for ready manipulation and can be applied or removed with great facility and with considerable ease on the part of the operator.

30 While the preferred form of the invention has been herein shown and described, it is to be understood that various changes may be made in the details of construction and in the combination 35 and arrangement of the several parts, within the scope of the claims, without departing from the spirit of this invention.

What is claimed as new is:—

1. A clamp embodying a body bent upon itself 40 to form opposed spaced walls, one of which walls terminates considerably short of the end of the other, a tongue pivoted to the shorter wall and forming a closure for the space therebetween and on one side of the pivot, an extension on said 45 tongue for swinging it about its pivot, a portion of said extension being shaped to form an open article holding recess, said recess being closed by the longer of said walls when said tongue is in an operative position to close the said space between 50 said walls, and ears at the ends of the tongues, said ears being deflected at an angle to the tongue to reinforce the tongue.

2. A clamp embodying a body bent upon itself to form spaced walls, one of which terminates 55 considerably short of the end of the other wall, a member pivotally connected intermediate its ends with the shorter wall, the end of said member on one side of the pivot being shaped to form a tongue to provide a closure for the space between 60 said walls, said member on the other side of the pivot being shaped to form an open recess, said recess being closed by the longer wall when the tongue is in a closing position, whereby two 65 separate article holding spaces will be provided one on each side of said pivot, and reinforcing means for the bent portion of said body.

3. A clamp embodying a body bent upon itself to form spaced walls, one of which terminates considerably short of the end of the other wall, 70 a member pivotally connected intermediate its ends with the shorter wall, the end of said member on one side of the pivot being shaped to form a tongue to provide a closure for the space be-

tween said walls, said member on the other side of the pivot being shaped to form an open recess, 5 said recess being closed by the longer wall when the tongue is in a closing position, whereby two separate article holding spaces will be provided one on each side of said pivot, and ears formed at the lateral edges of the tongue, said ears being deflected laterally with respect to the tongue to reinforce the latter.

4. A clamp embodying a U shaped body having 10 opposed spaced walls, the extremity of one of said walls terminating considerably short of the extremity of the other wall, a tongue pivoted to the shorter wall and forming a closure for the space between said walls, and an extension on 15 said tongue for swinging the tongue about its pivot, said extension beyond said pivot having an open recess, one wall of said recess when said closure is in operative position substantially abutting the said longer wall, to form with the last 20 said wall, a closed article receiving space.

5. A clamp embodying a U shaped body having opposed spaced walls, the extremity of one of said walls terminating considerably short of the extremity of the other wall, a tongue pivoted to 25 the shorter wall and forming a closure for the space between said walls, and an extension on said tongue for swinging the tongue about its pivot, said extension beyond said pivot having an open recess, one wall of said recess when said closure is in operative position substantially abutting the said longer wall, to form with the last 30 said wall, a closed article receiving space, said tongue being longer than the space between said walls, the tongue operating when moved about its 35 pivot to spring the walls, said tongue being held in an operative closed position by the springing action of said walls.

6. A clamp embodying a U shaped body having 40 opposed spaced walls, the extremity of one of said walls terminating considerably short of the extremity of the other wall, a tongue pivoted to the shorter wall and forming a closure for the space between said walls, and an extension on said 45 tongue for swinging the tongue about its pivot, said extension beyond said pivot having an open recess, one wall of said recess when said closure is in operative position substantially abutting the said longer wall, to form with the last said wall, a closed article receiving space, said tongue when 50 in an open position being folded back upon the outer face of the shorter wall, said tongue in the last said position co-operating with the longer of said walls to form a guide to position the clamp upon the support.

7. A clamp embodying a U shaped body having 55 opposed spaced walls, the extremity of one of said walls terminating considerably short of the extremity of the other wall, a tongue pivoted to the shorter wall and forming a closure for the space between said walls, and an extension on 60 said tongue for swinging the tongue about its pivot, said extension beyond said pivot having an open recess, one wall of said recess when said closure is in operative position substantially abutting the said longer wall, to form with the last 65 said wall, a closed article receiving space, said extension when said closure is in operating position to close the space between said walls, being substantially co-extensive with that portion of the said longer wall which is beyond the extremity of the said shorter wall.
